UNITED STATES PATENT OFFICE.

ARTHUR W. FISHER, OF FOREST HILLS BOROUGH, AND WESLEY B. WELLS, OF WILKINSBURG, PENNSYLVANIA, ASSIGNEES TO THE UNION SWITCH & SIGNAL COMPANY, OF SWISSVALE, PENNSYLVANIA, A CORPORATION OF PENNSYLVANIA.

RAILWAY APPARATUS.

Application filed June 6, 1923, Serial No. 643,766. Renewed December 20, 1926.

Our invention relates to railway apparatus, and particularly to apparatus of the type comprising track circuit including normally energized track relays arranged to be shunted by the wheels and axles of passing trains.

We will describe one form and arrangement of apparatus embodying our invention, and will then point out the novel features thereof in claims.

The accompanying drawing is a diagrammatic view showing one form of apparatus embodying our invention.

Referring to the drawing, the reference characters 3 and 3^a designate the track rails of a railway over which traffic normally moves in both directions. These track rails are divided by means of insulated joints 2 into two track sections A—B and B—C. Each section is provided with a suitable source of track circuit current such as a battery D which as here shown is connected with the rails adjacent the middle of the section. Interposed between each battery D and one rail 3^a of the associated sections is a resistance 1, one function of which is to limit the output of the battery when the rails of the section are occupied by a train. Connected across each end of each section is a track relay here designated by the reference character R with a distinguishing exponent.

As shown in the drawing, the juncture of sections A—B and B—C is located at the intersection of the railway and a highway M—N. This intersection is protected by a highway crossing signal controlled by means of an interlocking relay L of any suitable type. As here shown the crossing signal comprises a bell E provided with a circuit which passes from some suitable source of energy such as a battery J, through wire 50, back contact 51 operated by winding 46 of interlocking relay L, wire 52, operating mechanism of bell E, and wire 53, back to battery J. Another circuit is provided for bell E which passes from battery J, through wire 50, back contact 54 operated by winding 47 of interlocking relay L, wire 55, operating mechanism of bell E, and wire 53 back to battery J. It follows that bell E

will ring whenever either back contact of relay L is closed.

The interlocking relay L is controlled, as will appear hereinafter, by means of a slow acting relay H located at point B.

Each section is provided with a slow acting relay designated by the reference character F with a distinguishing exponent, and each section is further provided with a line relay designated by the reference character G with a distinguishing exponent.

Referring particularly to section B—C, line relay G³ is provided with a pick-up circuit which passes from a suitable source of energy as a battery K, through wires 4, 5, 6, 7 and 8, front contact 9 of track relay R⁴, wire 10, front contact 11 of track relay R³, wire 12, winding of line relay G³, wires 13 and 14, front contact 15 of slow acting relay F³ and wires 16, 17 and 18 back to battery K. This circuit is closed only when relays R³, R⁴ and F³ are all energized. This circuit is provided with a branch which passes from wire 13, through front contact 20 of line relay G³, and wires 21, 22 and 23, back to wire 17. The circuit through this branch is closed only when relay G³ is already energized and relays R³ and R⁴ are both energized, and so this circuit serves as a retaining or stick circuit for relay G³ but it cannot serve to energize this relay after relay G³ has been de-energized.

Slow acting relay H is provided with a circuit which passes from battery K through wires 4, 5, 6 and 7, back contact 24 of line relay G³, wires 25 and 26, winding of relay H, and wires 27, 23, 17 and 18 back to battery K. This circuit is closed only when relay G³ is de-energized. Slow acting relay F³ is provided with a circuit which passes from battery K through wires 4, 5 and 28, front contact 29 of slow acting relay H, wire 30, winding of slow acting relay F³, wires 31 and 32, back contact 20 of track relay R³, and wires 21, 22, 23, 17 and 18 back to battery K. This circuit is provided with a branch which passes from wire 31, through wire 33, front contact 34 of slow acting relay F³, wires 35 and 36, front contact 37 of line relay G², and wires 100

38, 39, 40 and 41 back to wire 18. It follows that relay F^3 can become energized only when relay H is energized and relay G^3 is de-energized, but that when relay F^3 once becomes energized it will remain energized as long as relay H is closed and relay G^2 is closed.

Interlocking relay L is provided with two windings 46 and 47. Winding 46 is provided with a circuit which passes from battery K through wires 4, 5, 6 and 7, front contact 24 of line relay G^3 , wire 42, back contact 43 of slow acting relay F^3 , wire 44, winding 46 of interlocking relay L, and wires 45 and 18 back to battery K. This circuit is closed only when relay G^3 is closed and relay F^3 is open.

Relay G^2 associated with section A-B is provided with a pick-up circuit similar to the pick-up circuit for relay G^3 of section B-C. This circuit includes front contact 56 of track relay R' , front contact 57 of track relay R^2 , and front contact 58 of slow acting relay F^2 . The stick circuit for relay G^2 includes the above-mentioned track relay contacts and front contact 59 of line relay G^2 , but omits front contact 58 of slow-acting relay F^2 . Relay F^2 is controlled over circuits similar to those described in connection with relay F^3 , the pick-up circuit for relay F^2 including front contact 60 of relay H and back contact 59 of line relay G^2 , and the stick circuit for this relay including front contact 60 of relay H, front contact 62 of relay G^3 , and front contact 61 of relay F^2 . It will also be noticed that the opening of relay G^2 closes, at back contact 48 thereon, a circuit for relay H, the purpose of which circuit will become apparent as the description proceeds. Winding 47 of interlocking relay is controlled by front contact 48 of relay G^2 and back contact 63 of relay F^2 in a manner similar to the control of winding 46 by relays G^3 and F^3 .

In the drawing all parts of the apparatus are illustrated in the conditions corresponding to the unoccupied condition of both sections A-B and B-C. All the track relays R' , R^2 , R^3 and R^4 are energized. Line relays G^2 and G^3 are also energized, whereas slow acting relays H, F^2 and F^3 are all de-energized. Both windings 46 and 47 of interlocking relay L are therefore energized and the bell E is therefore de-energized. Now we will assume that a train, moving toward the left, enters section B-C at point C. This de-energizes track relays R^3 and R^4 which in turn de-energizes line relay G^3 . The opening of front contact 24 of line relay G^3 interrupts the circuit for winding 46 which thereupon becomes de-energized and causes bell E to ring. The closing of back contact 24 of line relay G^3 completes the circuit for relay H which thereupon becomes energized. The closing of front

contact 29 of slow acting relay H completes the circuit for relay F^3 through back contact 20 of line relay G^3 and slow acting relay F^3 is then energized, closing its front contacts.

As the train enters section A-B, track relays R' and R^2 become de-energized. Relay G^2 is therefore immediately de-energized, and the opening of front contact 48 thereupon opens the circuit for winding 47 of relay L which thereupon becomes de-energized, but this happens before contact 51 opens and relay L is so constructed that under this condition the back contact 54 does not close. Relay H is already energized, and so the closing of back contact 59 of line relay G^2 energizes relay F^2 which closes its front contact.

As the rear of the train moves out of section B-C both track relays R^3 and R^4 are picked up and the closing of front contacts 11 and 9 on these relays completes the pick-up circuit for line relay G^2 through front contact 15 of relay F^3 now closed. As soon as front contact 20 of relay G^3 is closed the retaining or stick circuit therefor is closed and the relay is retained in its energized position regardless of the subsequent opening of contact 15 of relay F^3 . The winding 47 of interlocking relay L is not energized, however, for its circuit is still open at contact 43 of relay F^3 . The opening of back contact 24 of relay G^3 opens one circuit for relay H but this relay remains closed because of the circuit over back contact 48 of relay G^2 .

The opening of back contact 20 of relay G^2 opens one circuit for relay F^3 and the other circuit for this relay is already opened at contact 37 of relay G, therefore relay F^3 is de-energized. After an interval of time due to its retardation period relay F^3 closes its back contacts and thus completes the circuit for winding 46 of relay L. This winding is then energized, so that back contact 51 opens, but back contact 54 is still locked so that this contact is open. The bell E is therefore de-energized and stops ringing.

As the train passes out of section A-B, relays R' and R^2 are picked up, completing the circuit for relay G^2 which is then picked up thus de-energizing relay H. After an interval of time the front contacts of this relay open thus de-energizing relay F^2 but at the same time a shunting circuit is closed around this relay through the back contact 60 of relay H, thus delaying the release of relay F^2 beyond even its normal release period. When relay F^2 finally opens, the closing of its back contact 63 restores the circuits to normal by the energization of winding 47 of relay L.

The operation of the apparatus as a train passes from left to right is the same as that just described for traffic from right to left.

It will be observed that the pick-up circuit for relay G^3 is carried over a front contact of the relay F^2 . In a similar manner the pick-up circuit for relay G^2 passes over 5 a front contact on relay F^2 . The purpose of this is to insure continuous de-energization of relay L in the event of failure of either slow acting relay F^2 or F^3 to close.

If while a train is in section B-C moving 10 toward the left track relays R^3 and R^4 are momentarily energized, as by poor shunting due to rusty rails, relay G^3 will be momentarily picked up. While relay G^3 is closed the circuit will be broken for slow acting 15 relay H . Front contact 29 of this relay will not open, however, till the expiration of a definite time interval due to the period of retardation of this relay. Relay F^3 is energized over front contact 37 of relay G^2 , 20 which is now closed, and so relay F^3 will not be de-energized till relay H opens its front contact. When the front contact 29 of relay H opens, relay F^3 will become de-energized but its back contact will not close till the 25 expiration of a definite time interval. The duration of this time interval is considerably increased by "snubbing" or short circuiting the relay over the back point of contact 29 of relay H . It will thus be seen that 30 following the energization of relays R^3 and R^4 , the circuit for winding 46 of interlocking relay L is not completed, and hence bell E is not de-energized, till the expiration of the time interval required for relays H and 35 F^3 to successively close their back contacts. The parts may be so proportioned that the period of retardation thus provided exceeds the time interval during which relays R^3 and R^4 are closed, thus insuring constant operation 40 of signal E .

If section A-B is occupied by a train moving from right to left, winding 46 of relay L , as hereinbefore explained, is energized and winding 47 is de-energized. Contact 54 however is locked in its open position and bell E is therefore de-energized. If now winding 47 should become momentarily energized, contact 54 would be unlocked, and if winding 47 should subsequently be de-energized, the bell E would become energized. Since the train is moving away from the crossing at point B, the energization of bell E is undesirable. In our invention it will be observed that intermittent operation 55 of relay G^2 , due to intermittent energization of relays R^1 and R^2 , will not operate to energize winding 47 of relay L till the expiration of the time interval required for relays H and F^2 to successively close their 60 back contacts as explained hereinbefore in connection with section B-C, and so relay L will not be released by momentary failure of the shunt across the rails of section A-B.

It should be pointed out that although we 65 have herein shown and described our inven-

tion in connection with a highway crossing signal, it is in no way limited to such application.

Although we have herein shown and described only one form and arrangement of 70 railway apparatus embodying our invention, it is understood that various changes and modifications may be made therein within the scope of the appended claims without departing from the spirit and scope of our 75 invention.

Having thus described our invention, what we claim is:

1. In combination, two contiguous insulated sections of railway track, a single slow 80 acting relay controlled by traffic conditions in both said sections, two other relays one for each section controlled by said slow acting relay, and an electro-responsive device controlled in part by said other relays. 85

2. In combination, an insulated section of railway track, a track relay responsive to traffic conditions in said section, a line relay for said section, a slow acting relay controlled by said line relay, means controlled 90 by said slow acting relay for at times energizing said line relay, and signaling apparatus controlled in part by said slow acting relay.

3. In combination, two adjacent insulated 95 sections of railway track, a line relay for each section responsive to traffic conditions in such section, a common relay controlled by said line relays, a slow acting relay for each section controlled by said common relay, an interlocking relay having two windings, one of which windings is controlled by each line relay and the associated slow acting relay, and a highway crossing signal controlled by said interlocking relay. 100

4. In combination, two insulated sections 110 of railway track, a source of track circuit current for each section connected across the track rails adjacent the middle of the section, two track relays for each section connected across the rails adjacent the two ends of the section respectively, a line relay for each section, a slow acting relay for each section, a third slow acting relay common to 115 said two sections, means for energizing said third slow acting relay when either of said line relays is open, means operating to energize each of said first two slow acting relays when the associated line relay is open and the third slow acting relay is energized, 120 means for energizing each line relay when the two associated track relays are energized and the associated slow acting relay is energized, an interlocking relay having two magnets when and only when the associated 125 slow acting relay is open and the associated line relay is energized, and signaling means controlled by said interlocking relay.

5. In combination, an insulated section of 130 railway track, two track relays responsive to

- 4 traffic conditions in said section, a line relay controlled by said track relays, a slow acting relay, and means controlled by said line relay for energizing said slow acting relay or for de-energizing said slow acting relay and subsequently short-circuiting the terminals thereof. 70
6. In combination, an insulated section of railway track, two track relays responsive to traffic conditions in said section, a line relay controlled by said track relays, a slow acting relay, means controlled by said line relay for energizing said slow acting relay or for de-energizing said slow acting relay 75 and subsequently short-circuiting the terminals thereof, and railway signaling apparatus controlled by said slow acting relay.
7. In combination, an insulated section of railway track, two track relays responsive to traffic conditions in said section, a line relay controlled by said track relays, a slow acting relay, means controlled by said line relay for energizing said slow acting relay or for de-energizing said slow acting relay 80 and subsequently short-circuiting the terminals thereof, and railway signaling apparatus controlled by said slow acting relay and said line relay. 85
8. In combination, two contiguous insulated sections of railway track, a line relay for each section, means associated with each section and responsive to traffic conditions therein for controlling the associated line relay, a common relay at times controlled by each of the said line relays, a slow acting relay for each section controlled in part by said common relay, and apparatus controlled by said line relays and said slow acting relays. 90
9. In combination, two contiguous insulated sections of railway track, a line relay for each section, means associated with each section and responsive to traffic conditions therein for controlling the associated line relay, a common relay at times controlled by each of the said line relays, a slow acting relay for each section, means controlled by each line relay for energizing the associated slow acting relay, and means controlled by the line relay associated with the other section for energizing said slow acting relay. 100
10. In combination, two contiguous insulated sections of railway track, a line relay for each section, means associated with each section and responsive to traffic conditions therein for controlling the associated line relay, a common relay at times controlled by each of the said line relays, a slow acting relay for each section controlled by the associated line relay and the line relay for the other section, and a highway crossing signal controlled by said line relays and said slow acting relays. 110
11. In combination, two contiguous insulated sections of railway track, a line relay 115 for each section, means associated with each section and responsive to traffic conditions therein for controlling the associated line relay, a common relay at times controlled by each of the said line relays, a slow acting relay for each section controlled by the associated line relay and the line relay for the other section, and a highway crossing signal controlled by said line relays and said slow acting relays. 120
12. In combination, two contiguous insulated sections of railway track, a source of track circuit energy for each section, a track relay connected across the rails adjacent each end of each said section, a line relay and a slow acting relay for each said section, a common slow acting relay for the two said sections and located adjacent their junction, a circuit for each said line relay including a front contact on each associated track relay and a front contact on the associated slow acting relay, a circuit for said common slow acting relay comprising a front contact on one said line relay, a second circuit for said common slow acting relay including a front contact on the other said line relay, a circuit for each said slow acting relay including a front contact on said common slow acting relay and a back contact on the associated line relay, a second circuit for each said slow acting relay including a front contact on said common slow acting relay and a back contact on said common slow acting relay and a front contact on said slow acting relay, and an interlocking relay controlled by said line relays and said slow acting relays. 125
13. In combination, two sections of railway track, a track circuit including a track relay for each section, an individual slow-releasing relay for each section and a third slow-releasing relay common to the two sections, means operating when either track relay is open to energize said common relay, means operating when said common relay is closed and either track relay is open to energize the individual slow-releasing relay associated with such track relay, and signaling means controlled jointly by said track relays and said individual slow-releasing relays. 130
14. In combination, two sections of railway track, a track circuit including a track relay for each section, an individual slow-releasing relay for each section and a third slow-releasing relay common to the two sections, means operating when either track relay is open to energize said common relay, means operating when said common relay is closed and either track relay is open to ener- 135

gize the individual slow-releasing relay associated with such track relay, means operating when said common relay and the remaining individual slow-releasing relay are closed to 5 maintain said individual slow-releasing relay in its energized condition, and signaling means controlled jointly by said track relays and said individual slow-releasing relays.

15. In combination, two sections of rail-
10 way track, a track circuit including a track relay for each section, an individual slow-releasing relay for each section and a third slow-releasing relay common to the two sections, means operating when either track 15 relay is open to energize said common relay, means operating when said common relay is closed and either track relay is open to energize the individual slow-releasing relay associated with such track relay, and a snub-
20 bing circuit for each said individual slow-releasing relay including its own front contact and a back contact on said common relay.

16. In combination, two sections of rail-
25 way track, a track circuit including a track relay for each section, an individual slow-releasing relay for each section and a third slow-releasing relay common to the two sections, means operating when either track 30 relay is open to energize said common relay, means operating when said common relay is closed and either track relay is open to energize the individual slow-releasing relay associated with such track relay, and a highway 35 crossing signal controlled jointly by said track relays and said individual slow-releasing relay.

17. In combination, two sections of rail-
40 way track, a track circuit including a track relay for each section, an individual slow-releasing relay for each section and a third slow-releasing relay common to the two sections, means operating when either track 45 relay is open to energize said common relay, means operating when said common relay is

closed and either track relay is open to energize the individual slow-releasing relay associated with such track relay, an interlocking relay having one winding controlled by one of said individual slow-releasing relays and 50 the associated track relay and having the other winding controlled by the remaining individual slow-releasing relay and its associated track relay, and a highway crossing signal controlled by said interlocking relay. 55

18. In combination, two insulated sections of railway track, a source of track circuit current for each section connected across the track rails adjacent the middle of the section, two track relays for each section connected 60 across the rails adjacent the two ends of the section respectively, a line relay for each section, a slow acting relay for each section, a third slow acting relay common to said two sections, means for energizing said third slow acting relay when either of said line relays is open, means operating to energize each of said first two slow acting relays when the associated line relay is open and the third slow acting relay is energized, means 65 for subsequently keeping such first slow acting relay energized as long as the third relay is closed and the line relay for the other section remains closed, means for energizing each line relay when the two associated track 70 relays are energized and the associated slow acting relay is energized, means for subsequently keeping each line relay energized until one of the associated track relays opens, an interlocking relay having two magnets 75 80 one for each section, means for energizing each magnet when and only when the associated slow acting relay is open and the associated line relay is energized, and signaling means controlled by said interlocking 85 relay.

In testimony whereof we affix our signatures.

ARTHUR W. FISHER.
WESLEY B. WELLS.
